(57) **CLAIM**

The ornamental design for an in-store marketing sign, as shown and described.

DESCRIPTION

FIG. 1 is a front view of one embodiment of the in-store marketing sign.

FIG. 2 is a top view of the in-store marketing sign embodiment of FIG. 1.

FIG. 3 is a bottom view of the in-store marketing sign embodiment of FIG. 1.

FIG. 4 is a back view of the in-store marketing sign embodiment of FIG. 1.

FIG. 5 is a left side view of the in-store marketing sign embodiment of FIG. 1.

FIG. 6 is a right side view of the in-store marketing sign embodiment of FIG. 1.

FIG. 7 is a front view of a second embodiment of the in-store marketing sign.

FIG. 8 is a top view of the in-store marketing sign embodiment of FIG. 7.

FIG. 9 is a bottom view of the in-store marketing sign embodiment of FIG. 7.

FIG. 10 is a back view of the in-store marketing sign embodiment of FIG. 7.

FIG. 11 is a left side view of the in-store marketing sign embodiment of FIG. 7; and,

FIG. 12 is a right side view of the in-store marketing sign embodiment of FIG. 7.

The dashed lines in FIGS. 1-12 do not form any part of the claimed design for the in-store marketing sign.
